UNITED STATES PATENT OFFICE

HARRY R. JUDSON, OF ADA, OHIO, ASSIGNOR TO NATIONAL TUBE COMPANY, A
CORPORATION OF NEW JERSEY

MANDREL HANDLING MACHINE

Application filed May 20, 1932. Serial No. 612,567.

This invention is a machine for removing and replacing mandrels on the end of a mandrel bar between a pair of rolls, and is particularly adapted for use with seamless tube mills.

These mandrels are now manually handled and this involves a considerable amount of labor and some little danger, all of which this machine is intended to obviate.

Having reference to the accompanying drawing which illustrates specific examples of this invention,

Figure 1 is a side elevation of one form.

Figure 2 is a top plan of the first figure.

Figure 3 is a side elevation of another form. The preferred form of the machine as

shown by the drawing has a guide 1 alined in front of and below a mandrel bar 2 which holds a mandrel 3 between a pair of rolls 4.

This guide carries a sliding cross-head 5 to which one end of an arm 6 is pivoted.

The free end of this arm curves up toward the mandrel bar and has an electromagnet 7 on its free extremity. This electromagnet 25 has a face fitting the mandrel 3 and provides a mandrel holding means for the arm. The free end of this arm rides on a roller 8 on which it is held by a second roller 9 rockably mounted on an arm 10. A power driven crank 11 reciprocates the cross-head 5 by means of a connecting-rod 12.

In operation, the cross-head is reciprocated forward so that the arm 6 reaches upward and engages the mandrel 3. When the cross-head 5 is moved in the opposite direction the curved end of the arm 6 rides on the roller 8 and drops downwardly because of its shape. When in this position the mandrel may be removed and another substituted or if the same mandrel is to be used again it may be sprayed with water to cool it.

In the modified form of the invention a guide 13 is provided in place of the guide 1. This guide has an upwardly flared top surface 14, and a cross-head 15 fits in it. This cross-head 15 pivotally carries an arm 16 which is generally similar to the one originally described except that its dropping motion is accomplished by a projection 17 arranged near its pivoted end. This projection holds

the arm 16 so that it can engage the mandrel between the rolls when the cross-head is in its forward position. When the cross-head moves in the opposite direction the arm 16 drops because the projection 17 rides up the curved part of the surface 14. In this form, the arm 16 drops sufficiently so that a bosh 18 filled with water can receive and cool the mandrel on the end of the arm. In this case the cross-head 15 is reciprocated by a fluid motor 19 of the cylinder and piston type.

Although a specific form of the invention has been shown in accordance with the patent statutes, it is not intended to limit the scope of the invention exactly thereto, except as defined in the accompanying claims.

I claim:

1. A machine for removing and replacing mandrels on the end of a mandrel bar between a pair of rolls including an arm alined with said bar, means for mounting the end of said arm remote from said bar for reciprocatory movement alined therewith, means for guiding the free end of said arm upwardly when approaching said bar and downwardly when receding therefrom and mandrel-holding means on the free end of said arm.

2. A machine for removing and replacing mandrels on the end of a mandrel bar between a pair of rolls including a guide, a cross-head slidably carried by said guide, an arm having one end pivoted on said cross-head, means for controlling the pivotal action of said arm so its free end swings up adjacent the end of said bar when advanced theretowards and downwardly therefrom when moved in the opposite direction and mandrel-holding means on the free end of said arm.

3. A machine for removing and replacing mandrels on the end of a mandrel bar between a pair of rolls including a guide adjacent the end of said bar, a cross-head associated with said guide, an arm having one end pivoted to said cross-head and its other end extending towards said bar and curved upwardly, a surface between said guide and bar supporting the free portion of said arm, mandrel-holding means on the free

extremity of said arm and means for reciprocating said cross-head.

4. A machine for removing and replacing mandrels on the end of a mandrel bar between a pair of rolls including a guide adjacent the end of said bar and having an upwardly flared top surface at its end remote therefrom, a cross-head associated with said guide, an arm having one end pivotally carried by said cross-head and constructed with a projection sliding beneath said top surface to hold the free end of the arm in an upward position, mandrel-holding means on the free end of said arm and means for reciprocating said cross-head.

5. A machine for removing and replacing mandrels on the end of a mandrel bar between a pair of rolls comprising a guide alined in front of and below said bar, a cross-head slidably carried by said guide, an arm having one end pivoted to said cross-head and its other end extending towards said bar and curved upwardly, a roller holding up the free end of said arm, a rockably mounted roller holding said arm down on said first named roller, mandrel-holding means on the free end of said arm and means for reciprocating said cross-head.

In testimony whereof, I have hereunto set
30 my hand.

HARRY R. JUDSON.
